UNITED STATES PATENT OFFICE

WILLIAM L. SULLIVAN, OF FERGUSON, MISSOURI, ASSIGNOR TO NATIONAL ELECTRIC TICKET REGISTER COMPANY, OF ST. LOUIS, MISSOURI, A CORPORATION OF MISSOURI

TICKET-ISSUING MACHINE

Application filed August 13, 1927. Serial No. 212,704.

My invention relates to ticket issuing and registering machines such as are in general use in moving picture and other theaters and in which one or more tickets are delivered by the machine to the customer upon the pressure of an indicating key, or other operating element, by a ticket seller.

One example of a machine of this type is illustrated and described in my Patent No. 1,145,818 and my present invention consists in an attachment applicable to the machine described in said patent and serving to mark each ticket that passes through the machine, the main object of my invention being to render casual inspection of the tickets collected at the door either by sight or touch determinative of whether or not they have been passed through the ticket issuing machine. As all tickets which pass through the machine are counted, it will be seen that this functioning of my invention will serve as a check to prevent a dishonest or careless ticket seller from delivering tickets to a customer by hand, which tickets will not be registered by the counter of the ticket issuing machine.

Another object of my invention is to be able to identify the machine which has issued any particular ticket, this being of value in checking up on the operations of different ticket sellers where more than one ticket seller is employed at the same theatre or other place where machines of this type are used.

Another object of my invention is to positively actuate the ticket marking device so that no tickets can pass through the machine without being marked as is possible where the marking devices are actuated merely by friction between the ticket strip and the marking device.

Another object of my invention is to mark the ticket at the extreme edge and at points spaced from the ends of the ticket so that numbering or other printing which is usually placed across the end of the ticket will not be obliterated.

Another object of my invention is to provide a marking device which will be free of the ticket strip when the machine is at rest

so that the ticket strip may be removed and/or a new ticket strip inserted in the machine without interference from the ticket marking device.

In the accompanying drawings which illustrate a selected embodiment of my invention, I illustrate only the feed wheel and associated parts of the entire machine as the mechanism by which the feed wheel is operated does not form a part of my present invention and is well-known to those skilled in the art and is illustrated and explained in detail in my above-mentioned Patent No. 1,145,818. In these drawings—

Figure 1 is a vertical transverse section through the feed wheel, the element upon which it is mounted, and the marking device which forms the subject-matter of my present invention, and is taken substantially on the line 1—1 of Figure 2.

Figure 2 is a side elevation of the parts shown in Figure 1.

Figure 3 is an enlarged detail of the ticket marking elements.

Figure 4 is a view of the ticket after it has been marked.

Figure 5 illustrates modified markings which may be provided on different machines or at different times on the same machine.

The tickets issued by the machine are cut in any desired quantities from a continuous pre-printed ticket strip 1 which passes over a supporting plate or drum 2 having a medial slot through which the pins 3 of a feed wheel 4 project. The feed wheel is driven by engagement of a ratchet 5 with a pawl 6 pivoted on one of the spokes of the feed wheels, the ratchet 5 being driven by the operating mechanism of the machine in a well-known manner. The feed wheel pins 3 carry the ticket strip over the drum 2 and draw the ticket strip through the slot 7 provided in the top plate 8 of the machine.

The above-mentioned mechanism is mounted between side plates 9 and 10 and the left-hand plate 10 forms a guide for one edge of the ticket strip. The righthand plate 9 carries a plate 11 which forms a guide for the opposite edge of the ticket strip. The ticket

100

strip is held loosely against the feed wheel by the plates 12 which are pivoted at 13 to the side plates.

A hub 14 formed integrally with the feed wheel 4, or attached thereto, carries a gear 15 adjacent to side plate 9 and lying in the same plane as guide plate 11 which is cut away around the edge of the teeth of gear 15. A pinion 16 is driven by gear 15 and plate 11 is also cut away to accommodate this pinion. Pinion 16 is mounted on the side plate 9 by means of a stud 17. Pinion 16 carries a segment gear 18 which is positioned inside of the plane of gear 15, pinion 16, and guide plate 11 and is adapted to intermittently engage the surface of the ticket strip 1 as it passes over drum 2. A ring gear 19 is attached to gear 15 and meshes with the teeth of segment gear 18 whenever the latter are opposed as indicated in Figure 3.

Obviously the movement of the feed wheel positively drives gear 15, pin 16, and segment gear 18 whereby positive engagement and deformation of the ticket strip is provided intermittently when the ticket feeding mechanism is operated. It will be impossible for a ticket to be passed over the feed drum by the feed wheel without getting its edge crimped or otherwise marked as indicated at 20 on the ticket T illustrated in Figure 4.

It will be understood that the gears and pinions are so proportioned that one of the ends of segment gear 18 will be presented to the ticket strip as often as one of the feed pins 3 passes a given point. Hence each ticket will be deformed by the segment gear.

When the machine is at rest, the segment gear will be in the approximate position shown in Figure 2 in which none of its teeth engage the ticket strip and the ticket strip may be freely inserted or removed from the feed wheel as is necessary when the ticket supply is exhausted and a new roll or package of tickets is applied to the machine. It will be understood that this can only be done by a person having access to the ticket magazine of the machine or to that portion of the mechanism illustrated in Figure 2 which is usually closed by a door which may be locked.

I illustrate a method of physically deforming the ticket by merely placing a series of corrugations along one edge and spaced from its ends, but it will be understood that this marking may be varied and that the corrugations could be arranged in any of the forms indicated in Figure 5 or any other desired form. In a theatre where three or four machines are being used each machine could be adapted to form a different marking upon the ticket so that after the tickets were collected there would be an indication of which machine, and ticket seller, had issued and sold the ticket.

In Figure 2 I indicate the ordinary counter at 21 and the counter driving pinion at 22, the latter being driven by engagement with the gear 15 which also drives the pinion 16 and the marking gear 18.

With my device it is impossible for the marking elements to feed the ticket strip faster or slower than the feed wheel proper as would be the case if the marking elements were in continuous engagement with the ticket strip. From a practical standpoint, it would be impossible to have two devices, each tending to feed the ticket, in perfect synchronism with each other as a difference of only one-thousandth of an inch in the circumference of the two elements would result in buckling or tearing of a ticket after a few hundred had been issued. At the same time my device does not depend for its printing upon friction engagement of the marking elements by the ticket strip but is positively driven and positively engages each ticket fed through the machine.

Obviously variations in the details of construction may be made without departing from the spirit of my invention, and I contemplate the exclusive use of such modifications as fall within the scope of my claims.

I claim:

1. In a machine of the class described, ticket feeding mechanism including a gear wheel over which the ticket or ticket strip moves as it is being issued, and a segment gear immediately over the ticket or ticket strip and adapted to mesh with said gear wheel during a relatively short portion of the passage of the ticket thereover.

2. In a machine of the class described, a ticket strip feeding mechanism including a gear wheel over which the ticket strip moves as it is being issued, a gear adjacent to said wheel, a pinion in mesh with said gear, and segment gear carried by said pinion and adapted to mesh at intervals with said wheel and to distort a ticket strip passing between them.

3. In a machine of the class described, a ticket strip feeding mechanism including a gear wheel over which the ticket strip moves as it is being issued, a gear adjacent to said wheel, a pinion in mesh with said gear, segment gear carried by said pinion and adapted to mesh at intervals with said wheel and to distort a ticket strip passing between them, and means for guiding a ticket strip so that one edge passes between said gear wheel and segment gear.

4. In a machine of the class described, a ticket strip supporting drum, a ticket strip feed wheel having pins projecting through said drum, a gear fixed on said wheel, a pinion driven by said gear, a sector gear mounted on said pinion, and gear teeth moving with said feed wheel and meshing with said sector gear at intervals, said teeth and

said sector gear interengaging adjacent to the edge of said drum whereby a ticket fed by said wheel may be deformed by said teeth and said sector gear.

5. In a machine of the class described, a ticket strip supporting drum, a ticket strip feed wheel having pins projecting through said drum, a gear fixed on said wheel, a pinion driven by said gear, a sector gear 10 mounted on said pinion, and gear teeth moving with said feed wheel, said sector gear being adapted to mesh with said gear teeth as said feed wheel functions to deliver one or more tickets but being normally disengaged 15 from said gear teeth when said feed wheel is stationary, said pinion and gear teeth being located adjacent to the edge of said drum whereby a ticket fed by said wheel may be deformed by said sector teeth and said gear teeth but a ticket strip may be passed over said drum without interference by said sector gear when the machine is at rest.

In testimony whereof I hereunto affix my signature this 10th day of August, 1927.

25 WILLIAM L. SULLIVAN.
